UNITED STATES PATENT OFFICE.

FREDERICK O. BALL, OF DETROIT, MICHIGAN ASSIGNOR TO BALL & BALL CARBURETOR COMPANY, OF DETROIT, MICHIGAN, A CORPORATION OF MICHIGAN.

REATOMIZER.

1,392,473.

Specification of Letters Patent.

Patented Oct. 4, 1921.

Application filed September 4, 1920. Serial No. 408,242.

To all whom it may concern:

Be it known that I, FREDERICK O. BALL, a citizen of the United States, residing at Detroit, in the county of Wayne and State 5 of Michigan, have invented new and useful Improvements in a Reatomizer, of which the following is a specification.

This invention is designed to atomize the liquid which is carried into the passages 10 leading to an explosive engine by reason of the precipitation of the liquid from the mixture or from a failure to fully atomize the liquid in the carburetor usually used. What are commonly known as hot spots 15 have been provided for vaporizing the unatomized liquid but these are subject to certain disadvantages particularly in view of the fact that the heating of the mixture expands the air and consequently reduces the 20 quantity which will be drawn into the cylinder with a resultant reduction in power. With this invention the liquid which accumulates in the passages is drawn into what I term a re-atomizer, in which the liquid is 25 collected and again subjected to a spraying action of air so as to be broken up and fully atomized. This is accomplished regardless of the temperature of the engine and is also accomplished without adding 30 heat to the air and in its preferred form is carried out without adding any moving parts to the apparatus.

The invention is illustrated in the accompanying drawing wherein 1—1 mark two 35 engine cylinders. As many cylinders as desired may be used, the manifold 2 extending to the different cylinders. The manifold has the inlet 3 with the branches 4 leading from each side of the inlet.

40 Any desired carburetor 5 may be used. In the one shown 6 marks the mixing chamber, 7 the primary throat leading to the mixing chamber, 8 the secondary throat leading to the mixing chamber, 9 the float chamber, 10 the fuel conduit leading from the float chamber, 11 a metered opening in the fuel chamber, 12 a spray nozzle leading to the primary throat and connected with the fuel conduit, 13 an air opening for introducing air for spraying the liquid 45 through the nozzle 12, 14 a metered opening leading to an intermediate chamber 15, 16 a spray nozzle leading from the chamber 15, 17 an air opening leading to the 50 chamber 15 and furnishing air for spraying the fuel to the secondary throat, 18 the main throttle at the discharge side of the mixing chamber, and 20 a throttle controlling the passage through the secondary throat. These features of the carburetor 55 may be, as before stated, varied as desired and in themselves form no part of my invention.

The re-atomizer is in the form of a fitting 60 having flanges 22 through which screws 23 extend to secure the fitting to the carburetor and having a flange 24 by means of which it may be secured to the manifold. The re-atomizer is provided with a throat 25 having a very slight restriction and 65 spray nozzles 26 lead into this throat. The spray nozzles lead from the collecting annulus 27. The collecting annulus has an annular slot 28 extending through the bottom of the annulus adjacent to the wall, the nozzles 26 extending into the restriction 70 formed by the throat have their ends in the path of high velocity and in consequence a very much reduced pressure relatively to the pressure in other parts of the passage. 75 As a result a movement of air or mixture at a very high velocity is induced through the nozzles 26 from the drawing of air from the annulus 27 and through the slots 28. Any liquid, therefore, that may be accumulated 80 on the walls of the carburetor or the passage above it which is carried along up these walls by the action of the air is caught 85 by the slot 28 and carried into the annulus 27 and is sprayed by the action of the air 90 through the nozzles 26, thus being very largely atomized through the spraying action in the nozzles themselves and is again subjected to the high velocity of air in the 95 throat so that such liquid is completely atomized. In this way the liquid which ordinarily accumulates in the wall of the carburetor and which ordinarily can only be removed therefrom by a very high velocity of 100 air or heat is entirely removed, and thus the carburation which the carburetor is intended to affect is not interfered with.

Some liquids may be carried through the throat 25 and some of the mixture which has been previously atomized may be precipitated on to the walls of the passage at 105 the discharge side of the throat 25. I preferably provide, therefore, an annular cup or

socket 28^a in the upper edge of the throat 25 and connect this cup by a passage 29 with the collecting annulus 27 where it is taken up by the spray nozzles and re-
5 atomized.

The liquid is also deposited and collects in the depressions in the manifold. In many designs it is difficult to avoid such depressions by reason of the requirements 10 of the manifold. The liquid fuel accumulates in these depressions and interferes with the proper functioning of the engine, being usually finally carried into the engine in liquid form. I prefer to connect such de-
15 pressions as 30 by means of pipes 31 to a common pipe 32 leading to a passage 33 communicating with the collecting annulus 27 where such liquid is carried through the nozzles 25 and sprayed in the manner above
20 described. It will be understood that the pressure at the nozzles will be somewhat less than the pressure at the depressions 30 so that there will be a difference in pressure at the ends of the passages connecting
25 the depressions with the collecting annulus. Gravity also aids in the movement of the liquid.

It will be noted that there is no opening leading from the outer air to any of the 30 passages between the engine and the carbureter. Consequently there is no disturbance in the action of the carbureter.

What I claim as new is:

1. In a reatomizer, the combination of a 35 wall forming a mixture passage; a liquid collector opening from said wall and intercepting ingoing liquid from said wall; and means for driving the fuel from the collector by a current of gaseous fluid passing
40 through the collector and spraying the liquid into the mixture passage.

2. In a reatomizer, the combination of a wall forming a mixture passage; a liquid collector opening from said wall and intercepting ingoing liquid from said wall; and means for driving the fuel from said collector by a current of gaseous fluid passing through the collector and by variations of pressure in different parts of the mixture 50 passage and spraying the fuel into the mixture passage.

3. In a reatomizer, the combination of a wall forming a mixture passage; a liquid collector opening from said wall and intercepting ingoing liquid; means inducing a current of mixture through the opening; and means returning the fuel collected into the current of mixture in the mixture passage.

60 4. In a reatomizer, the combination of a wall forming a mixture passage; a liquid collector opening from said wall and intercepting ingoing liquid; means inducing a current of mixture through the opening; and means returning the fuel collected into
65

the current of mixture in the mixture passage through the discharge of the mixture drawn into the opening.

5. In a reatomizer, the combination of a wall forming a mixture passage; a collector 70 opening from the wall and intercepting ingoing liquid; a connection leading from the collector to a point in the passage having less pressure than at the opening leading to the collector whereby there is a forced draft into and out of the collector.

6. In a reatomizer, the combination of a wall forming a mixture passage; a collector opening from the wall and intercepting ingoing liquid; a connection leading from the 80 collector to a point in the passage having less pressure than at the opening leading to the collector whereby there is a forced draft into and out of the collector, said connection terminating in a nozzle extending 85 into the mixture current away from the wall of the passage.

7. In a reatomizer, the combination of a wall forming a mixture passage; a collector opening from said wall and intercepting an 90 ingoing liquid; and means discharging the liquid collected to the mixture current at a point in the passage inwardly from the opening to the collector.

8. In a reatomizer, the combination of a 95 wall forming a mixture passage; a collector opening from said wall and intercepting an ingoing liquid; and means discharging the liquid collected to the mixture current at a point in the passage inwardly from the opening to the collector.

9. In a reatomizer, the combination of a wall forming a mixture passage; a collector opening from said wall and intercepting an 105 ingoing liquid; and means discharging the liquid collected to the mixture current at a point in the passage inwardly from the opening to the collector through a draft of gaseous fluid through the collector, said fluid being drawn in through the opening 110 from the wall and spraying the liquid as it is discharged.

10. In a reatomizer, the combination of a wall forming a mixture passage comprising a restricted throat; a collector opening 115 from the wall and intercepting ingoing liquid; and a connection leading from the collector to the passage at the restriction.

11. In a reatomizer, the combination of a fitting adapted to be inserted in a mixture 120 passage to form a part of said passage and comprising a collector having an opening adapted to intercept ingoing liquid, and a connection leading from the collector to the passage at a point of lower pressure than the opening.

12. In a reatomizer, the combination of a fitting adapted to be inserted in a mixture 125 passage to form a part of said passage and comprising a collector having an annular

opening adapted to intercept ingoing liquid, and a connection leading from the collector to the passage at a point of lower pressure than the opening.

5 13. In a reatomizer, the combination of a fitting adapted to be inserted in a mixture passage to form a part of said passage and comprising a restriction, a collector having an opening adapted to intercept ingoing liquid, and a connection from the collector to the passage at the restriction.

10 14. In a reatomizer, the combination of a fitting adapted to be inserted in a mixture passage to form a part of said passage and comprising a restriction, a collector having an opening adapted to intercept ingoing liquid, and a connection from the collector to the passage at the restriction, the discharge of the connection being remote from 20 the wall of the passage.

15 15. In a reatomizer, the combination of a wall forming a mixture passage; a liquid collector; and a spraying device comprising a nozzle leading to the passage from the collector and a connection leading to the collector from the passage at a point of higher pressure than the nozzle, the flow of mixture through the connection and nozzle inducing 25 a flow of liquid from the passage to the collector and spraying the liquid from the collector through the nozzle.

30 16. In a reatomizer, the combination of

a wall forming a mixture passage; a liquid collector; and a spraying device comprising a nozzle projecting from the wall of the passage into the mixture current and leading from the collector and a connection leading to the collector from the passage at a point of higher pressure than the nozzle, the flow of mixture through the connection and nozzle inducing a flow of liquid from the passage to the collector and spraying the liquid from the collector through the nozzle.

35 17. In a reatomizer, the combination of a wall forming a mixture passage; a liquid collector; a connection leading from the passage to the collector, the entrance from the passage to the collector being nearer the discharge of the passage than the collector; a second connection leading from the passage to the collector, the point of entrance from the passage to the connection being nearer the entrance to the passage than the collector; and a nozzle leading from the collector to the passage and spraying the liquid collected in the collector into the mixture current through the passage, the entrances to each connection being at a point of higher pressure than the discharge end of the nozzle.

40 45 50 55 60 In testimony whereof I have hereunto set my hand.

FREDERICK O. BALL.
